UNITED STATES PATENT OFFICE

CARL J. JOHNSON AND AARON B. JOHNSON, OF LOUISVILLE, KENTUCKY

ELECTROTHERAPEUTICAL INSTRUMENT

Application filed June 6, 1927. Serial No. 196,918.

This invention provides an instrument utilizing the Oudin, Tesla or monopolar current of a high frequency machine for dehydrating, desiccating or coagulating tissues 5 of the human body without the grounding of the current through the body of the patient subjected to treatment.

While the drawing illustrates a preferred embodiment of the invention, it is to be understood that in adapting the means to meet specific needs and requirements the design may be varied and such other changes in the minor details of construction may be resorted to within the scope of the invention as 15 claimed, without departing from the spirit thereof.

For a full understanding of the invention and the merits thereof, reference is to be had to the following description and the 20 drawing hereto attached in which,—

Figure 1 is a vertical, central longitudinal, sectional view of an electrical instrument of the character aforesaid embodying the invention.

25 Figure 2 is a front view of the instrument.

Figures 3 and 4 are side views of different forms of electrodes adapted to be interchangeably fitted to the body of the instrument.

30 Corresponding and like parts are referred to in the following description and designated in the several views of the drawing by like reference characters.

The body 1 of the instrument is elongated 35 and slender and is provided at one end with a grip 2, which preferably forms a part of the body. The body and grip are preferably formed of insulating material, such as hard rubber, Bakelite and the like. These parts 40 may be molded or formed in any preferred way and contain openings for the passage of elements 3, 4 and 5. The elements 4 and 5 consist of wires or conductors for electricity. The element 3 consists of a needle which is 45 slidably fitted within the body 1 and projects at opposite ends, the front end being pointed and the rear end having a button 6 of insulating material fitted thereto. An open coil spring 7 is mounted upon the rear 50 projecting end of the needle 3 and is con-

fined between the rear end of the body and a stop collar 8 fast to the rear projecting end of the needle and operates to normally hold the point of the needle in retracted position. A plate 9 is secured to the rear end of the body 1 and the needle 3 operates therethrough. The wire 5 is connected at one end to the plate 9 and its opposite end is connected to a screw 10 or like element applied to the end of the grip 2. An electric cord 11 is connected to the screw 10 and may be plugged into an outlet or connected to a source of current in any well known manner. A metal plate 12 is fitted to a side of the grip 2 and the current is grounded thereby through the operator. The wire 4 is connected at one end to the plate 12 and its opposite end projects beyond the front end of the body 1 and is adapted to have an electrode 13 fitted thereto.

Various forms and sizes of electrodes are provided and are adapted to be selectively or interchangeably fitted to the projecting end of the electric conductor 4. The electrodes usually consist of a stem, and a pressure head, the stem being formed with a socket to receive the projecting end of the electric conductor 4 which, in the preferable construction are connected by means of a screw-thread joint, as indicated most clearly in Figure 1 of the drawing. The head of the electrode is generally of annular form, as indicated most clearly in Figure 2, and may be of any diameter depending upon the extent of tissue to be treated.

When the instrument is in active service it is held in the hand of the operator by means of the grip 2, and is applied by placing the head of the electrode 13 in contact with the tissue to be treated. Pressure is now exerted upon the button 6 with the result that the needle 3 is pressed forward and its point caused to penetrate the tissue. It is assumed that the current is on and enters the tissue through the needle and passes off by way of the electrode 13, and is grounded through the operator by means of the wire 4 and plate 12. The flow of the high frequency current dehydrates, desiccates and coagulates the tissue, the degree of such ac-

tion depending upon the density of the tissue, the strength of the current and the length of time the current is permitted to flow.

5 Having thus described the invention, we claim:

1. A therapeutic instrument for the practice of electro-coagulation and desiccation by means of high frequency currents comprising an elongated body having a grip at one end, a needle slidably mounted upon the body, electric conductors passing through the body and grip, one of said conductors being electrically connected with the needle, an 10 electrode connected to the other electric conductor and adapted to coact with the said needle, and a metal plate applied to the grip and having the electric conductor of the electrodes connected thereto, whereby to ground 15 the current through the operator.

2. A therapeutic instrument for the practice of electro-coagulation and desiccation by means of high frequency currents comprising a body having an offstanding grip at one 25 end, a needle slidably mounted within the body, and having its pointed end projecting at the front thereof, means for supplying an electric current to the needle, an electrode fitted to the front of the body, and a current 30 grounding plate fitted to the grip and electrically connected with the said electrode.

3. A therapeutic instrument for the practice of electro-coagulation and desiccation by means of high frequency currents, the same 35 comprising a stem, and a pressure head of annular form at one end of the stem, and perpendicular thereto.

4. A therapeutic instrument for the practice of electro-coagulation and desiccation by 40 means of high frequency currents comprising a body provided with a grip, a needle slidably mounted in the body and projecting beyond the ends thereof, a metal plate fitted to the rear end of the body and having the needle 45 operating therethrough, an electric conductor within the grip, and connected to the said plate, an electrode at the front end of the body adapted to coact with the said needle, a plate applied to the grip for grounding the 50 current through the operator, and an electric conductor connecting the said electrode with the current grounding plate.

5. A therapeutic instrument for the practice of electro-coagulation and desiccation by 55 means of high frequency currents comprising a slender body provided at one end with an offstanding grip, a metal plate fitted to the rear end of the body, a needle slidably mounted within the body and plate, and projecting 60 beyond opposite ends of the body, an open coil spring mounted upon the rear projecting end of the needle, a current grounding plate applied to the grip, an electric conductor passing through the grip and body and connected 65 at one end with the current grounding plate

and having its opposite end projecting beyond the front of the body, an electrode selectively fitted to the projecting end of the electric conductor.

In testimony whereof we affix our signatures.

CARL J. JOHNSON. [L. S.]

AARON B. JOHNSON. [L. S.]
